C. TYMM

RAIL BRIDGE

Filed Aug. 18. 1923

UNITED STATES PATENT OFFICE.

CECIL TYMM, OF LOUISVILLE, KENTUCKY.

RAIL BRIDGE.

Application filed August 18, 1923. Serial No. 658,074.

To all whom it may concern:

Be it known that I, CECIL TYMM, a citizen of the United States, residing at the city of Louisville, county of Jefferson, State of Kentucky, have invented new and useful Improvements in Rail Bridges, of which the following is a specification.

This invention relates to an improvement in rail bridges and particularly to a bridge which is interposed between the adjoining ends of two rails and supported by the adjoining rails for forming a continuous rail surface to eliminate the jarring and vibrations created by the wheels of a vehicle passing from one rail to another.

The invention consists in providing the end of each rail with two holes or recesses of different bores to receive a pin or bridge of such form as to provide a smooth travelling surface from one rail to the other.

The invention consists of certain novel features of construction and combinations of parts which will be hereinafter described and pointed out in the claims.

25 In the accompanying drawings—

Figure 1 is a top plan view;

Figure 2 is a view in side elevation partly in section;

Figure 3 is an end view of a rail; and

30 Figure 4 is a perspective view of the pin or bridge and an end of a rail.

Each rail consists of the usual ball or tread 10, base flanges 11 and web 12. At the ends of each rail is formed in the tread or ball 10 a cylindrical recess 13 which is parallel to the tread of the rail and is exposed to a suitable width in the tread of the rail. This opening or exposed portion 14 in the tread is of less width than the width of the 35 recess 13. Another recess 15 is formed in the end of the rail and parallel to the tread, and is a continuation of the recess 13, but of a smaller bore or diameter.

The bottom of the recess 15 is on the same 45 level with the bottom of the recess 13, and the center of the recess 15 is below the center of the recess 13.

A pin or bridge consists of an enlarged cylindrical portion 16, conforming to the 50 cylindrical recess 13 of the rail, having a flat or truncated upper surface 17 which conforms with the upper surface of the ball 10 of the rail. On each end of the enlarged portion 16 are shanks 18, 18, of less diameter than the portion 16, which fit the recesses 15 of the rail ends. The shanks 18

are eccentrically arranged with respect to the enlarged portion 16 whereby they will fit the recesses 15, and prevent the bridge 60 from rotating.

The shanks 18 of the bridge are received in the recesses 15 of the rail ends, while the enlarged portion 16 fits the recesses 13, and the flat portion 17 conforms to the surface of the rail tread or ball and fills the opening 65 14 formed in the tread in the formation of the recess 13.

With this construction the shanks permit of the expansion and contraction of the rails and maintain them in alinement and insure 70 the retention of the enlarged portion 16 in proper position between the intersecting ends of the rails to form a continuous travelling surface from one rail to the other.

The two rails are joined together by means 75 of fish plates 19, 19, and bolts 20.

Having described my invention, what I claim is:

1. The combination of rails each having two recesses in each end thereof, one of 80 which recesses is a continuation of the other and of a smaller bore and the bottom of the smaller recess is on the same level with the bottom of the larger recess, and a bridge interposed between the rail ends and composed of an enlarged central portion to fit a recess in an end of each rail, and cylindrical shanks of uniform diameter on opposite sides of the enlarged portion received 85 in the recesses of the smaller bores. 90

2. The combination of rails, each having two recesses in each end thereof parallel to the tread of the rails, one of the recesses of each rail extending through the tread of the rail and the first mentioned recess being 95 a continuation of the other and of a smaller bore, and a bridge interposed between the rails composed of an enlarged cylindrical portion fitting and conforming to the recesses of the rail ends and truncated on its 100 upper surface to conform and aline with the tread of the rail, and shanks on opposite sides of the enlarged portion received in the recesses of the smaller bores.

3. The combination of rails each having 105 two recesses in each end thereof, one of which recesses is a continuation of the other and of a smaller bore, and a bridge interposed between the rail ends and composed of an enlarged cylindrical portion to fit a recess in an end of each rail, and shanks on 110 opposite sides of the enlarged portion ar-

ranged eccentrically thereto and received in the recesses of the smaller bores and preventing rotation of the bridge.

4. The combination of rails each having two recesses in each end thereof, one of which recesses is a continuation of the other and of a smaller bore and the bottom of the smaller recess is on the same level with the bottom of the larger recess and a bridge 10 interposed between the rail ends and composed of an enlarged central portion to fit a recess in an end of each rail, and shanks on opposite sides of the enlarged portion arranged eccentrically thereof and received in the recesses of the smaller bores and preventing rotation of the bridge.
5. The combination of rails each having two recesses in each end thereof, one of 20 which recesses is a continuation of the other and of a smaller bore and the bottom of the smaller recess is on the same level with the

bottom of the larger recess and a bridge interposed between the rail ends and composed of an enlarged central portion of a 25 uniform cross section to fit a recess in an end of each rail, and shanks on opposite sides of the enlarged portion arranged eccentrically thereof and received in the recesses of the smaller bores and preventing rotation of 30 the bridge.

6. A rail splicing structure including the rails having axially alined recesses in their adjacent ends, and a bridge having an enlarged cylindrical portion provided with a truncated upper side, and cylindrical shanks 35 projecting from the ends of the enlarged intermediate portion and engaging said recesses, the said intermediate portion and shanks being of a uniform cross-section respectively throughout their extent, and having their bottom surfaces lying in horizontal planes.

CECIL TYMM.
